UNITED STATES PATENT OFFICE.

JOHN H. HERSHBERGER, OF WILKES-BARRE, PENNSYLVANIA.

HORSESHOE.

1,191,002.

Specification of Letters Patent. Patented July 11, 1916.

Application filed September 17, 1913. Serial No. 790,274.

To all whom it may concern:

Be it known that I, JOHN H. HERSHBERGER, a citizen of the United States, residing at Wilkes-Barre, in the county of Luzerne and State of Pennsylvania, have invented new and useful Improvements in Horseshoes, of which the following is a specification.

An object of the invention is to provide a horseshoe for aiding horses in gaining and retaining a foot-hold on slippery surfaces such as pavements and the like.

The invention contemplates, among other features, the provision of a horseshoe body carrying toe and heel calks which can be readily secured rigidly on the body and which include cutting edges which will cut into ice on slippery pavements and the like and aid the horse in gaining a strong foot-hold, thus preventing the horse from slipping or falling.

In the further disclosure of the invention reference is to be had to the accompanying drawings, constituting a part of this specification, in which similar characters of reference denote corresponding parts in all the views, and in which:

Figure 1 is a perspective view looking at the under side of the horseshoe, showing the arrangement of the calks thereon; Fig. 2 is a vertical transverse sectional view taken through the body of the horseshoe and the toe calk; Fig. 3 is a perspective view looking downwardly on one of the calks; and Fig. 4 is a fragmentary plan view looking into one of the milled grooves, with a calk thereof removed therefrom.

Referring more particularly to the views, I provide a shoe body 10 having a substantially U-shape and similar to the ordinary horseshoe, the said shoe body at its medial or toe portion having a dependent socket 11 preferably formed therewith and provided with a longitudinally milled circular groove 12 forming parallel flanges 13, a toe calk 14 being adapted to be supported in the socket 11, with the said toe calk including a shank 15 having a gripping edge 16 and a head 17 consisting of similar parallel circular flanges 18, the said flanges extending longitudinally to the shank 15 and tapering toward one end with respect to the

shank so that the toe calk 14 can be arranged in the milled groove 12, with the flanges engaging the milled portions of the 55 groove, thus rigidly binding the toe calk in the socket 11.

The heel portions of the shoe body 10 are provided with sockets 19 constructed similarly to the socket 11 and heel calks 20 similar in construction to the toe calk 14 are adapted to be arranged in grooves 21 formed in the sockets 19 on the heel portions of the shoe body, the heel calks 20, however, having their gripping edges adapted to lie in 60 the plane of movement of the hoof of the horse, whereas the gripping edge 16 of the toe calk 14 extends transversely to the plane of movement of the hoof of the horse, thus insuring a positive grip on slippery pavements and surfaces.

From the foregoing description it will be noted that my device is of a simple and durable construction, consisting substantially of a plurality of heel calks and a similar toe 75 calk, all of which are similarly mounted upon the heel portions and toe portion respectively of a shoe body which is preferably formed of a single piece of metal, the sockets 11 and 19 being preferably formed 80 with the shoe body at the medial and end portions thereof.

With a horseshoe of the character described it will be apparent that when one of the calks becomes worn and unfit for use it 85 can be readily driven out of the socket in which it normally lies and a new calk inserted therein, the said calks being held in the sockets by the frictional engagement of the heads of the calks with the milled surfaces of the grooves formed in the sockets.

Having thus described my invention, I claim:

In a device of the class described, in combination a horse shoe formed with a pair of 95 hook-shaped flanges forming a socket between them, each of said flanges having a substantially semi-circular inner edge and an outwardly beveled edge, the circular edges of said flanges formed in a plane with 100 the flat surface of the horse shoe while the beveled edges thereof converge outwardly of the socket, and a calk consisting of a substantially V-shaped projection having

lateral extending semi-circular flanges adapted to snugly fit the semi-circular edges of said socket, said calk being provided with a concave edge at its base joining said semi-circular flanges and arranged immediately opposite the flat surface at the base of said socket.

In testimony whereof I affix my signature in presence of two witnesses.

JOHN H. HERSHBERGER.

Witnesses:

J. Q. CREVELING,
JOSEPHINE SCHMITT.
